TRIPPLICATE MANIFOLDING BOOK

Albert R. Lawson, Hamilton, Ontario, Canada,
assignor, by mesne assignments, to American
Sales Book Company, Limited, Toronto, On-
tario, Canada, a corporation of Canada

Application April 19, 1930, Serial No. 445,610

4 Claims. (Cl. 282—22)

This invention relates to that type of manifolding book in which three copies are to be made at one writing. The simplest book of this type at present used is the so called "automatic" in which the backs of the upper two of three sheets are carbonized. This is open to the grave objection that the sheets are dirty to handle and cannot be wrapped up with soiled goods. Another type, free from this objection, uses two fixed carbon sheets which have to be handled each time the book is used. This latter book is thus complicated, troublesome to use and is wasteful of time. Further, as the same carbon sheets are repeatedly used, the last copies made are apt to be illegible.

My object therefore is to produce a manifolding book which will be as convenient to use as the "automatic", which will produce as clean sheets or checks as the type using separate carbon sheets and which will possess the further advantage that two or more of the sheets of a set or unit may be removed with their registration retained and a carbon sheet in position between them.

I attain my object by binding to a suitable back a plurality of manifolding units each comprising a triplicate sheet, an original sheet integral therewith and normally folded in parallel thereto, a duplicate interposed between the original and triplicate, and a carbon sheet folded to lie between the original and duplicate and the duplicate and triplicate, the carbon sheet being carbonized alternately on opposite sides to present carbonized surfaces to the upper faces only of underlying sheets.

Each unit is connected to the back, preferably by providing both the duplicate and triplicate sheets with stubs bound to the back.

The carbon sheet will usually be secured by gumming to the end of the triplicate sheet adjacent the stub.

The invention is hereinafter more specifically described and is illustrated in the accompanying drawing in which

Fig. 1 is a perspective view of one unit of the book comprising an original sheet, a duplicate sheet, a triplicate sheet, and a carbon sheet gummed at one end to the triplicate;

Fig. 2 a side elevation of a unit, showing the carbon sheet provided with a stub whereby it may be bound in the book;

Fig. 3 a similar view showing the duplicate, triplicate and carbon sheets united to a common stub;

Fig. 4 a perspective view of a book constructed

in accordance with my invention as it appears when ready for the making of an entry on an original sheet; and

Fig. 5 a perspective view showing an original and triplicate sheet removed with the carbon sheet still in place.

In the drawing like numerals of reference indicate corresponding parts in the different figures.

Referring particularly to Fig. 1 of the drawing, it will be seen that each manifolding unit comprises a triplicate sheet 1 provided with a stub 2, an original sheet 4 united to the free end of the triplicate sheet, a duplicate sheet 5 provided with the stub 6 and a carbon sheet 3 which is folded parallel to the line of juncture of the original and triplicate sheets to lie between the original and duplicate sheets and between the duplicate and triplicate. The end of the carbon sheet adjacent the stubs is gummed to the face of the triplicate sheet. By means of the stubs 2 and 6 the units are bound together to form a book as shown in Fig. 4 of the drawing.

The book is provided with a cover which includes at least a back 7 and a portion 8 bound to the stub of the book.

It will also usually include a front 9 and stop sheet 10 connected, preferably integrally, with the free end of the back 7 so that it may be used as hereinafter described.

The originals, duplicates and triplicates may be printed, as usual, according to the requirements of the purchaser, and may be numbered consecutively either from the front to back or the back to the front of the book. The stop sheet also acts as a record sheet on which a summary of sales may be entered. Perforations or other lines of weakness will usually be employed to facilitate the separation of the originals from the triplicates and the latter from their stubs.

In a book constructed as in Figs. 1 and 4 of the drawing the duplicates are usually left in the book and the triplicates and originals removed, the carbon sheets remaining in position and attached to the triplicate sheets.

For some purposes it may not be essential to have the carbon sheets attached to the triplicates, in which case each carbon sheet may be formed with a stub 11 whereby it may be bound in the book and may or may not be torn off with the original and triplicate.

If it is desired to remove each unit as a whole the construction shown in Fig. 3 may be employed in which a single stub 12 is provided for binding into the book to which the duplicates, triplicates and carbon sheets are all connected.

One connection will usually be integral, the others necessarily by gumming. With this construction each unit is removable as a whole and in the folded condition.

- 5 As a separate carbon sheet is provided for each manifolding unit I find it desirable in order to avoid making the book too bulky and expensive to use for the carbon sheets a very thin cheap paper having a very light coating of carbon applied thereto. To further keep down expense, and to make for cleanliness in handling each carbon sheet is carbonized alternately on opposite sides to present carbonized surfaces to the upper faces only of the underlying sheets when a unit 10 is being used for entries.

Working from the front the method of use of this book is as follows. With the parts in the position shown in Fig. 2 the first original sheet is exposed. The entries are made on the original sheet and transferred to the duplicate and triplicate. The original and carbon sheet are then turned back out of the book by grasping the free margin of the original and the underlying end of the carbon sheet which is left clean 15 of carbon as shown so that the fingers are not soiled in this operation. The triplicate can then be readily separated from its stub by a suitable sideways pull on the original, the separated parts then appearing as in Fig. 5. The leaves thus 20 separated from the book can be refolded with the carbon sheet still retained in place and the writing on the original and copies still in register. Further inscriptions, check marks or 25 signatures may thus be added on the original as needed and duplicated. If desired a unit after use may be turned back over the cover, while 30 a second unit is being used, and is thus subsequently conveniently available if further entries are to be made thereon.

40 In working the book from the back all the units, except the one to be used, are thrown back over the cover and the stop sheet positioned under the one to be used. After use the original, triplicate and carbon sheet are removed as hereinbefore described and the duplicate sheet positioned under the stop sheet.

If the unit used is to be kept in the book for any purpose it is positioned under the stop sheet ready to be brought up over the same if further 50 entries are to be made.

This book, it will be seen, may be used for any purpose where two copies of an original are required.

It is also particularly adapted for use where 55 a sales check is sent out with goods and the merchant is desirous of having a receipt for delivery appear on both sales checks.

For such purposes the original and triplicate 60 sheets with the carbon sheet between are sent out with the goods. To the original the recipient affixes his signature together with any notes or comments, if any, all of which is reproduced on the triplicate. The original is then torn off, leaving 65 the carbon attached to the triplicate. One

sales check is left with the consignee and the other taken back to the consignor. At any time after it has served its purpose the carbon sheet may be torn off and thrown away.

This form of triplicate book, it will be seen, is 5 inexpensive to manufacture, as the printing, numbering, folding, inserting and the pasting of the carbon sheets may be done expeditiously by automatic machinery. The carbon sheets being made as described of thin, cheap, lightly coated paper, 10 the book is neither too bulky nor too expensive as compared with the present triplicate books. The book is also clean to handle, as it is never necessary to touch the carbon surfaces, and when the carbon sheet is folded only non-carbonized surfaces are exposed. As none of the record sheets 15 are carbonized on the back, these surfaces are available for advertisements.

What I claim as my invention is:

1. A manifolding book comprising a plurality 20 of manifolding units each comprising a sheet normally folded to provide two relatively superposed record leaves, a carbon sheet folded parallel to the fold in the record sheet to provide two carbon leaves between said record leaves and having a 25 clean, free margin underlying the free margin of the folded record sheet, and a third record sheet disposed between said carbon leaves, one of said record sheets being bound in the book and the other record sheet being detachable with the two 30 carbon leaves, as a unit, from the book, independently of said bound sheet.

2. A manifolding book comprising a plurality of manifolding units each comprising a sheet normally folded to provide two relatively superposed 35 record leaves, a carbon sheet folded parallel to the fold in the record sheet to provide two carbon leaves between said record leaves, and a third record sheet disposed between said carbon leaves, one of said record sheets being bound in the book, 40 and the other record sheet and the carbon sheet being secured to said bound sheet for detachment therewith as a unit from the book.

3. A manifolding book comprising a plurality of manifolding units each comprising a sheet 45 normally folded to provide two relatively superposed record leaves, a carbon sheet folded to provide two carbon leaves between said record leaves, and a third record sheet disposed between said carbon leaves, each of said record sheets being 50 bound in the book, said carbon sheet being secured to one of said record leaves so as to be detachable therewith as a unit from the book.

4. A manifolding book comprising one or more manifolding units, each unit comprising a record 55 sheet normally folded to provide two relatively superposed record leaves, a carbon sheet folded parallel to the fold in the record sheet to provide two carbon leaves between said record leaves, and a third record sheet interposed between said carbon leaves and having a detachable stub bound in the book, said folded record sheet and said carbon sheet attached to said third sheet outside said stub.

ALBERT R. LAWSON. 65
